TUBE EXPANDER

Frank Yochem, St. Louis, and Clarence E. Bodine,
Sedalia, Mo.

Application March 13, 1939, Serial No. 261,482.

7 Claims. (Cl. 153—81)

This invention relates to improvements in devices for expanding boiler tubes.

It is an object of this invention to provide an improved device of this type, which will safely and efficiently expand, roll, and bell boiler tubes.

Many devices used for this purpose are driven out of the tubes and injury to workers from flying parts is not uncommon. It is an object of this invention to provide a device which may be safely 5 removed from the tubes after the expanding operation is completed.

The use of the device provided by this invention in the manner described, expands the tube in the tube sheets in such a manner as to prevent 10 longitudinal movement of the tube.

With this device, it is possible to expand, roll, and bell a number of tubes without changing the position of the driving motor and thus considerably reduce the work and time required to roll 15 the tubes of a boiler.

Further objects and advantages will appear from the following detailed description and accompanying drawings.

For the purposes of illustration, I will now describe one form of the device which I have found to operate satisfactorily.

Fig. 1 is a longitudinal sectional view of one form of my device as applied to a locomotive.

Fig. 2 is a side view of the expanding rollers 30 and cooperating cage employed with my device.

Fig. 3 is a longitudinal cross-sectional view of the rollers and cage in position in a boiler tube.

Fig. 4 is a longitudinal cross-sectional view of the rollers in position in a boiler tube arranged 35 to show in detail the mandrel and its connection to the driving tube.

Throughout all the drawings, the same reference numerals are used to denote similar parts.

In the drawings, 11 indicates generally a locomotive provided with a firebox 13, back tube sheet 15, and front tube sheet 17. 19 is a tube or flue, 21 the smoke box and 23 the stack. It is understood, of course, that for purposes of illustration, only one tube 19 is shown although there are, of 45 course, many more.

25 is the crown sheet and 27 the boiler shell. 29 is an air motor supported from the front of the locomotive 31 by a bracket 33 and adjustable hanger 35.

50 The expander roller assembly 37 is shown in detail in Figs. 2 and 3. Rollers 39 are positioned in a cage 41. The cage is designed to position the rollers at a slight angle θ to the axis of the bore 43. The rollers may be held loosely in the 55 cage by pins 45 which project into recesses 47 at

one end of the rollers. A bushing 49 is threaded into the cage 41 and an annular flanged member 51 is carried by the cage. A tapered mandrel 53 is inserted through the bore 43 of the bushing and in between the rollers. I have found that the number of rollers used seriously affects the operation of the device and that an odd number of rollers and more particularly five, should be used to produce the best results.

A strip of copper 55 may be inserted between 10 the tube 19 and sheet 15 if desired. One end of the mandrel is provided with a square end 59 which may be inserted into a cooperating recess 61 in a coupling 63. The coupling 63 is secured to a tube or rod 65 in any suitable manner as by 15 a rivet 66. The tube 65 is supported in the tube 19 by washers 67. The other end of the tube 65 is coupled to the driving motor 29 by coupling 68 and shaft 69.

In order to expand the tubes in one sheet of a 20 boiler, the driving motor 29 is mounted at the opposite end thereof and connected to the drive tube 65 by the proper couplings and drive shafts. The mandrel 53 and roller assembly 37 are then 25 inserted in the end of the tube so that the square end of the mandrel will fit into the coupling 59.

The drive motor is then started in the proper direction to cause the inclination of the rollers to 30 pull the mandrel in. As the mandrel moves in, the rollers will be pressed farther and farther 35 apart and the rolls will expand, bell, and roll the tube as shown in Fig. 3. The sloping portion 70 of the roller will flare the tube at the outer end, while the portion 72 will form a bead or recess on the inside of the tube sheet. The straight surface 73 will roll the tube tightly in the tube sheet. The beads formed by these rollers will hold the tube so that it cannot move longitudinally in the tube sheet. A sloping portion 74 of the roller 40 produces a gradual slope from the beaded portion to the unexpanded portion of the tubes. This slope prevents an abrupt offset in the tube which would weaken it considerably. An abrupt offset 45 may reduce the life of a tube as much as 30%. After the tube is properly expanded, the rotation of the driving motor is reversed to release the roller assembly in the tube. Such a method of 50 removing the roller possesses distinct safety features as many injuries to workmen have been caused by the expanding tools being driven out by hammers, etc. Such injuries are made more likely in other types of expanders because of the necessity of having more than one man in the fire-box. With the device of this invention, only 55 one man need be in the fire-box, since the driving

motor is supported at the opposite end of the boiler.

It is not necessary to move the driving motor after each expanding operation. The drive tube 5 is merely shifted to the next tube. Since these driving motors are extremely large and require several men to move them, this advantage is readily appreciated. After all the tubes are rolled at the ends opposite the driving motor, the 10 near ends may be rolled without moving the driving motor by inserting the rollers and cage and driving the mandrel directly from the shaft 69. Thus both ends of a large number of tubes may be rolled with this device without changing the 15 position of the driving motor.

By use of the device of this invention, it is possible to considerably reduce the time required for expanding the tubes of a boiler, since expanding, 20 rolling, and belling are completed in one operation without setting up the driving motor for each tube. The particular roller assembly forms a bead which secures the tubes against any longitudinal movement and provides a more durably expanding job. This device makes it possible to 25 remove the expander without endangering life or limb of the workers, and yet the device is itself more effective than previous devices not possessing these advantages.

While we have described and illustrated one 30 form of device embodying our invention and one method of using the same, it is understood that various modifications, substitutions, omissions, and additions will appear to those skilled in the art and we do not wish to limit ourselves by the 35 above description and drawings but define our invention by the appended claims.

We claim:

1. A boiler tube expanding device comprising a driving motor supported at one end of a boiler, 40 a roller cage assembly provided with a mandrel and cooperating rollers and adapted to be inserted in the boiler tubes at the opposite end of the boiler, means extending through the boiler tube being rolled to connect the driving motor with the mandrel of the roller cage assembly.

2. A boiler tube expanding device comprising a driving motor supported at one end of a boiler, a roller cage assembly adapted to be inserted in the ends of the boiler tubes opposite the driving 50 motor, said roller cage assembly comprising a cage provided with recesses at an angle to the axis of the tube being rolled, rollers positioned in the recesses and a tapered mandrel encircled by the rollers, means extending through the tube being rolled to connect the driving motor with the mandrel for rotation thereof.

3. A boiler tube expanding device comprising a driving motor supported at one end of a boiler, a roller cage assembly adapted to be inserted in 60 the ends of the boiler tubes opposite the driving motor, said roller cage assembly comprising a cage provided with five recesses at an angle to the axis of the tube being rolled, rollers positioned in the recesses and a tapered mandrel en-

circled by the rollers, means extending through the tube being rolled to connect the driving motor with the mandrel for rotation thereof.

4. In a boiler tube expanding device, a driving motor supported at one end of a boiler, a roller 5 cage assembly adapted to be inserted in the tubes at the opposite end of the boiler comprising a cage provided with a plurality of recesses, rollers positioned in the recesses and a tapered mandrel encircled by the rollers, the recesses being inclined to the axis of the cage to cause the rollers to cooperate with the mandrel taper to draw the mandrel into the tube and press the rollers apart when it is rotated in one direction and to loosen the mandrel when it is rotated in the opposite 10 direction, and means extending from the driving motor to the mandrel within the tube being rolled to rotate the mandrel.

5. In a boiler tube expanding device, a driving motor supported at one end of a boiler, a roller 20 cage assembly adapted to be inserted in the tubes at the opposite end of the boiler comprising a cage provided with five recesses, rollers positioned in the recesses and a tapered mandrel encircled by the rollers, the recesses being inclined to the 25 axis of the cage to cause the rollers to cooperate with the mandrel taper to draw the mandrel into the tube and press the rollers apart when it is rotated in one direction and to loosen the mandrel when it is rotated in the opposite 30 direction, and means extending from the driving motor to the mandrel within the tube being rolled to rotate the mandrel.

6. In a boiler tube expanding device a driving motor supported at one end of a boiler, an expander assembly adapted to be inserted in the tube at the opposite end of the boiler comprising an odd number of rollers, a member positioning the rollers around the inner periphery of the boiler tube at an inclination to the axis of 40 the boiler tube, a tapered mandrel encircled by the rollers and arranged to cooperate with the inclined rollers to cause the mandrel to be drawn into the boiler tube and press the rollers apart when rotated in one direction and to be loosened 45 when rotated in the opposite direction and means for driving the mandrel to extend from the driving motor through the tube being rolled to the mandrel.

7. A boiler tube expanding device comprising a 50 driving motor supported at one end of a boiler, an extension shaft connected with said driving motor, a roller cage assembly provided with a mandrel and cooperating rollers and adapted to be inserted in either end of the tubes of the 55 boiler, means to connect the extension shaft to the mandrel when inserted in the end of a boiler tube adjacent the driving motor and a connecting shaft extending through the boiler tube being rolled to drive the mandrel when inserted in 60 the end of the boiler tube opposite the driving motor.
